Primary Examiner—Bruce W. Dunkins

[57] CLAIM

The ornamental design for an extendible bedside table, substantially as shown and described.

DESCRIPTION

FIG. 1 is a perspective view from the top, front and right side of an extendible bedside table in the closed position according to my new design;

FIG. 2 is a perspective view from the bottom, rear and left side thereof, and,

FIG. 3 is a perspective view from the top, front and right side of the bedside table of FIG. 1 in the extended position.
